(57) **CLAIM**

The ornamental design for a holder for swivel connection to a support device, as shown and described.

DESCRIPTION

FIG. 1 is a perspective view of a holder for swivel connection to a support device;

FIG. 2 is a right side view of the holder for swivel connection to a support device shown in FIG. 1,

FIG. 3 is a left side view of the holder for swivel connection to a support device shown in FIG. 2,

FIG. 4 is a front view of the holder for swivel connection to a support device shown in FIG. 1,

FIG. 5 is a rear view of the holder for swivel connection to a support device shown in FIG. 1,

FIG. 6 is a top view of the holder for swivel connection to a support device shown in FIG. 1; and,

FIG. 7 is a bottom view of the holder for swivel connection to a support device shown in FIG. 1.

In the holder for swivel connection to a support device a swivel connection is provided for swivel engagement of the holder with the support device. The support device is adapted to hold an apparatus such as cell phone, a GPS or a tablet.

In FIG. 5, the features shown by dashed lines are not part of the claimed design.
